LÉON PALOUS, (F BERLIN, GERMANY.

TWO-CYCLE EXPLOSION-MOTOR.

1,041,154.

Specification of Letters Patent. Patented Oct. 15, 1912.

Application filed December 26, 1911. Serial No. 667,799.

To all whom it may concern:

Be it known that I, LÉON PALOUS, a subject of the King of Prussia, German Emperor, residing at Wilmersdorf, Berlin, in the Empire of Germany, have invented a new and useful Two-Cycle Explosion-Motor, of which the following is a specification.

My invention relates to improvements in two-cycle explosion motors of the kind, in which gas is sucked into the crankshaft casting or a special chamber and is compressed therein, or in which fresh air alone is sucked into the crankshaft casting or a special chamber and is slightly compressed therein, after which gas is admitted into the slightly compressed air prior to admission to the combustion chamber, and my improvement has for its object to essentially simplify the motor by omitting complicated positively driven organs. According to my invention a special mixing chamber valve is provided in a valve box on the cylinder, which mixing chamber valve normally divides a middle valve chamber communicating with the crankshaft casting or special chamber through a channel in the jacket of the cylinder from the upper valve chamber, which communicates through a by-passage and a narrow opening with the lower valve chamber that in turn communicates with an inlet in the cylinder. A vertical channel is provided in the valve box terminating in the bottom of the lower valve chamber and serves for supplying liquid combustible. The mixing chamber valve is by its spindle rigidly connected with a small valve controlling the said channel for liquid combustible. The piston is on its upper side provided with a bent tube, the lower inner end of which normally faces the inside of the cylinder and is adapted to periodically register with the inlet for receiving the stream of mixture, while the upper outer end of the tube is adapted to conduct the stream of mixture upward into an igniting vessel on the cover, so that at the end of the upward stroke of the piston the compressed mixture can be ignited by contact with the igniting vessel heated by the compression of the mixture. On the piston reaching its lowest position it uncovers the inlet, whereupon the compressed air from the crankshaft casting or special chamber, which meanwhile had opened the mixing chamber valve and passed through the upper valve chamber, the by-passage and the narrow opening into the

lower valve chamber, sucks in liquid combustible from the channel and injects it through the bent tube upward into the cylinder. The channel in the jacket passing around the outlet serves for preliminarily heating the compressed air on its way to the middle valve chamber.

I will now proceed to describe my invention with reference to the accompanying drawing, which represents a vertical cross section through the improved two-stage explosion motor.

18 denotes a closed crankshaft casing, in which the crankshaft 19 having cranks 20 is mounted to turn. On the casing 18 is fastened a cylinder 2, which is shown to have a jacket 22 communicating with an inlet 23 and an outlet 24 for the cooling water. The jacket 22, however, does not include the whole cylinder 2 but only a part of the same as there is a channel 5 left. The cylinder 2 has an air-inlet 3, an inlet 14 for the mixture and an outlet 4 for the spent products of combustion. The air-inlet 3, the inlet 14 and the outlet 4 pass through the jacket 5 and are therefrom separated by tubular walls, as is clearly shown surrounding the ports 4 and 14. The channel 5 passes around the outlet 4 and communicates on the one hand with the casing 18 through a mouth 21 and on the other hand with an opening 6. A valve-box 25 is fastened on the cylinder 2 and comprises three superposed valve chambers 31, 7 and 8, of which the middle chamber 7 communicates with the mentioned opening 6 and the lower chamber 8 with the inlet 14. The top of the middle valve chamber 7 forms a seat for a mixing chamber valve 9, which is rigidly connected with a vertical spindle 11 and opens into the upper valve chamber 31, which communicates through a by-passage 27 and a narrow opening 12 with the lower valve chamber 8. The spindle 11 is suitably guided in the partition 26 and in the cover of the valve box 25 and its lower tapering end in the lower valve chamber 8 is made to normally close a narrow channel 10 provided in the valve box and connected with a tube 13 for liquid combustible.

The cover 28 of the cylinder 2 is provided with a pear-shaped igniting vessel 17, which communicates with the upper space 16 in the cylinder 2. At the lower end the cylinder 2 is provided with two opposite recesses 29, in which the connecting rod 30

is permitted to engage as usual. The recess 29 on the right is not visible, as the channel 5, which may be assumed to be on the side of the cylinder 2 opposite to the air-inlet 3, is shown as turned through an angle of 90°, in order to show its construction.

The piston 1 is on its upper side provided with a bent tube 15, the lower inner end 15^a of which normally faces the inside of the cylinder 2 and can periodically register with the inlet 14, while the upper end is directed upward and can engage in the mouth of the igniting vessel 17 for the highest position of the piston 1, as is indicated by dotted lines. The height of the piston 1 happens to be equal to its stroke, that is equal to double the length of the crank 20, whereby the following explanations are simplified. For the highest position of the piston 1 its lower end *g*—*h* will occupy a position indicated by the dotted line *e*—*f*, so that it uncovers the lower part of the air-inlet 3. The inlet 14 is so disposed, that it is above the line *e*—*f* and consequently remains closed by the piston 1. At the same time the upper end *e*—*d* of the piston 1 will occupy a position indicated by the dotted line *a*—*b*, so that the horizontal portion of the bent tube 15 remains just beneath the underside of the cover 28 and its vertical portion engages in the mouth of the igniting vessel 17 as explained above. The outlet 4 of course remains closed by the piston 1. For the lowest position of the piston 1 its lower end *g*—*h* may occupy a position indicated by the dotted line *i*—*j*, while its upper end *c*—*d* occupies a position indicated by the dotted line *e*—*f*, so that the inlet 14 and the outlet 4 are uncovered by the piston and the lower end 15^a of the bent tube 15 registers with the inlet 14.

The two-cycle explosion motor described operates as follows: When the piston 1 occupies its highest position, both the inlet 14 and the outlet 4 are closed, while the air-inlet 3 is uncovered, so that air is permitted to enter the lower portion of the cylinder 2 and the interior of the crankshaft casing 18. Of course also the channel 5 from the mouth 21 up to the opening 6 and the middle valve chamber 7 are filled up with air sucked in during previous cycles of the motor, which air is preliminarily heated by contact with the hot walls of the outlet 4. When the piston 1 descends, it soon closes the air-inlet 3 and compresses the air below and forces it from the cylinder 2 into the crankshaft casing 18, so that the air contained in the casing 18, the channel 5 and the middle valve chamber 7 attains a certain pressure and opens the mixing chamber valve 9 and thereby also the channel 10 for liquid combustible, whereupon the compressed air fills up the by-passage 27 and through the opening 12 also the lower valve

chamber 8 and the inlet 14 to the periphery of the piston. Before the piston 1 attains its lowest position the inlet 14 will commence to be uncovered by the lower end 15^a of the bent tube 15, so that the stream of compressed air from the opening 12 will suck in from the channel 10 liquid combustible and inject it through the inlet 14 and the bent tube 15 into the cylinder 2 upward. The expelling of spent gases will be accomplished during the motion of the piston 1 down to its lowest position and through a small portion of the up-stroke until the piston 1 closes the outlet 4. Of course the injection of mixture will have ceased at the moment, that the piston 1 again closes the inlet 14, after which the mixing chamber valve 9 by reason of its own weight closes its seat and by the tapering end of the spindle 11 also the channel 10. Thereupon the fresh mixture in the upper portion 16 of the cylinder 2 will be compressed during the upward motion of the piston 1. About at the moment that the piston 1 attains its highest position the hot igniting vessel 17 will have been so much heated by the compression of the mixture as to ignite the mixture and thus to produce an explosion. The power of the expanding gases forces the piston 1 during the following stroke downward until the outlet 4 is uncovered by the piston, whereupon a part of the spent products of combustion at once escapes from the cylinder 2 through the outlet 4. During the up-stroke of the piston, just described, the piston creates a vacuum in crank-shaft casing 18, and as soon as the lower end *g*—*h* of the piston reaches a point to uncover the air inlet 3, the air is sucked or drawn into the casing 18 ready to be forced through passage 21 into the preliminary compression and heating chamber 5, from which it is conducted, as described, to the mixing chamber 8 ready to be discharged through inlet 14 into the tube 15^a. The downstroke of the piston does not uncover the air inlet 3; the inflow of air to the chamber 16 is caused by the compression of air in the crank shaft casing 18 and chamber 5, which is compressed by the piston to a pressure a little higher than the atmosphere. Afterward the whole series of occurrences described above will be repeated.

The two-cycle explosion motor presents the advantage, that a pump for sucking in air is dispensed with and consequently all danger of the formation of a wrong mixture is avoided. At the same time all complicated and positively driven devices for the injection of the liquid combustible are saved. Any kind of liquid combustible can be used for working the explosion motor, that is not only the lighter combustibles, such as benzine and the like, but also the heavier hydrocarbons and oil, which means,

that also carburetors are saved by the new simplified explosion motor.

The two-cycle explosion-motor can be varied in many respects without departing 5 from the spirit of my invention.

I claim:

1. In an explosive motor of the type described, a piston cylinder, a piston, a water chamber substantially surrounding the upper portion of said cylinder and having an inlet for the water at the lower portion of said cylinder, an air compression chamber substantially incasing the lower portion of said cylinder, a valve-box having three superposed valve chambers, the central of said chambers communicating with said compressed air chamber, the upper of said valve chambers being positioned above and extending around said central valve chamber, and communicating with the lower valve chamber, said lower valve chamber operating to communicate with the piston chamber upon the down stroke of the piston, means for introducing fuel into said lower valve chamber, and a valve operated by the compression of air upon each stroke of the piston for simultaneously admitting air to the upper valve chamber and fuel to said lower valve chamber.
2. In an explosive motor of the type described, a piston cylinder, an air compression chamber and a water chamber substantially incasing said cylinder, a valve-box positioned exteriorly of the piston cylinder, said valve-box containing three superposed valve chambers, the middle of which chambers communicates with the air compression chamber, and also with the upper valve chamber, said upper valve chamber communicating with the lower valve chamber, a source of fuel supply
- communicating with the lower valve chamber, a member separating said middle valve chamber and said lower valve chamber, a valve operable by the compression of air on the down stroke of the piston for regulating the passage of air from said middle valve chamber to said upper valve chamber and lower valve chamber, respectively, and a spindle carried by said valve and operating upon the movement of said valve to simultaneously admit fuel to said lower valve chamber when air is admitted thereto, for the purpose specified.
3. In an explosive motor of the type described, the combination, with an air compression chamber, a piston chamber, and a piston, of a valve-box provided with three superposed valve chambers, a member closing the upper part of said upper valve chamber, another member separating the middle valve chamber from the lower valve chamber, and a valve operating to control the passage of compressed air from the air compression chamber and the middle valve chamber to the upper valve chamber and the lower valve chamber, respectively, the upward movement of said valve being controlled by the down stroke of the piston, a fuel port to said lower valve chamber and a spindle secured to said valve and operating to control the passage of fuel through said fuel port to said lower valve chamber simultaneously with the admission of air to said lower valve chamber, for the purpose specified.

LÉON PALOUS.
